SHOE HEEL CONSTRUCTION

Robert D. MacDonald, Grosse Pointe Park, Mich.

Application February 12, 1936, Serial No. 63,484

2 Claims. (Cl. 36—36)

This invention relates to shoe heels. More particularly it relates to a novel form of resilient shoe heel which is adapted for easy application to a heel structure of a shoe and which will be retained in position thereon by means of the resiliency of the material of which it is formed.

The present invention contemplates the provision of a shoe heel construction in which the wear receiving element is easily and conveniently mounted on the shoe heel and is retained in position thereon without the necessity of auxiliary fastening means, such as nails or screws heretofore required in constructions of this general character.

15 The present invention contemplates the provision of a resilient shoe heel which is so constructed and formed that it will have an interfitting and interlocking relation with the shoe heel structure with which it is associated in order 20 to provide a protective covering for all sides thereof.

Still further, the invention contemplates a displaceable heel construction which is particularly easily mounted in position and which, when once 25 mounted in position, will be firmly and permanently secured in place.

Yet another object of the invention consists in the provision of a resilient shoe heel element which is adapted to cooperate with a fixed portion 30 of the shoe heel to provide an interlocking relation therebetween.

Still further, the present invention contemplates the provision of a construction which utilizes not only the tension of the deformable material of which the heel is disposed, but also the compression forces set up therein for the purpose 35 of securing the shoe heel element in position.

Many other and further objects and advantages of the present invention will become apparent 40 from the following specification when considered in connection with the accompanying drawing forming a part thereof.

Fig. 1 illustrates in side elevation a shoe having the improved heel construction embodied 45 therein.

Fig. 2 illustrates a shoe with the removable resilient heel element removed therefrom.

Fig. 3 is a transverse sectional view taken substantially on the line 3—3 of Fig. 1, showing in detail the interfitting engagement between the removable portion of the heel structure and the permanently mounted portion thereof.

Fig. 4 is a bottom plan view of the permanently mounted portion of the heel structure.

Fig. 5 is a top plan view of the removably mounted portion of the heel structure.

Figs. 6 to 9 inclusive are top plan views of several modified forms of removable heel elements embodying the same general principles of 5. 5: securement shown in the construction of Figs. 1 to 5, inclusive.

Fig. 10 is a transverse sectional view through a modified form of heel construction providing an exterior appearance substantially the same as 10 conventional rubber heels.

Fig. 11 is a top plan view of the removable heel element shown in Fig. 10.

Fig. 12 is a transverse sectional view similar to Fig. 3, illustrating a still further modified form 15 of the invention.

With more particular reference to the drawing, particularly the embodiment thereof illustrated in detail in Figs. 1 to 5, inclusive, the structure of the present invention comprises a permanently mounted heel member 10 which is secured 20 to the shoe structure by means of conventional clinched nails 11 driven therethrough and clinched interiorly of the shoe structure. This heel structure 10 has an outer configuration substantially the same shape as the heel structure 25 desired but slightly smaller. This heel member 10 is undercut adjacent the shoe to which it is secured around its entire periphery to provide a sharp shouldered channel 12 extending inwardly 30 from the outer periphery of the heel structure adjacent the sole of the shoe.

It has been found particularly desirable, as will hereinafter be more clearly seen, to form this permanently mounted heel 10 of rubber or suitable similar resilient composition material in order to facilitate the securement of the removably mounted heel member thereon. However, it will be clearly appreciated that in certain instances this permanently mounted heel member 40 may be formed of leather or metal or equivalent composition as may be desired.

A pair of channels 14 are formed in the bottom side of the permanently mounted heel member 10, and as will be seen by reference to Figures 3 45 and 4, these channels are of considerably greater width in their base portions than at the openings thereof, consequently providing a dovetailed recess for the reception and securement of the removably mounted heel member hereafter 50 described in detail. These channels preferably extend from points relatively widely spaced at the rear portion of the heel member to meet substantially in the central portion of the front of the heel member, it having been found that this part 55

ticular construction provides exceptionally strong securement of the removably mounted heel member at the particular points where such strength of securement is necessary and desirable.

5 A removably mounted heel member 15 formed of rubber is provided with an exterior configuration of a shape and size adapted to form the exposed portion of the heel construction and has an interior configuration adapted to mate with and 10 engage all of the available surfaces of the permanently mounted heel member 10. It will be seen that this heel member 15 is provided at its upper edge with an inwardly projecting flange 16 adapted to seat in the undercut portion 12 of the 15 permanently mounted heel member.

It will also be seen that this removably mounted heel member 15 is provided with dovetail portions 17 adapted to seat in the dovetail grooves 14 and engage substantially all surfaces thereof. It will 20 be noted by reference to Fig. 3 that these dovetail portions 17 are substantially wider at their top portions than at their bases in order to provide a substantial interlocking engagement of the removably mounted member 15 with the permanently mounted heel member 10.

The removably mounted heel member is necessarily formed of rubber or similar elastic resilient composition material and may easily be deformed sufficiently to slip over the heel member 10 and 30 may be hammered into place in order that the dovetail portions 17 will be seated in interlocking engagement in the grooves 14 in the permanently mounted heel member. Due to the resilient construction of which the removably mounted heel 35 member is composed, it will be held by tension in the undercut portion or channel 12 of the permanently mounted heel member and disposed in a condition of compression within the grooves 14 in the permanently mounted heel member. 40 Consequently, both forces of tension and compression are utilized for permanently securing this removably mounted member in place.

From the above described construction, it will be apparent that once the removably mounted 45 heel element 15 has been firmly seated in place, the combination of the tensionally interlocked portions and the compressionally interlocked portion will cooperate to provide an exceptionally strong interfitting relation between the component parts of the heel structure. Further, it 50 will be appreciated that the unsightly joints normally occurring between the leather and rubber portions in conventional rubber heel mountings is entirely eliminated in the construction of the 55 present invention and that the heel structure provided has an extremely attractive exterior appearance. It will be further appreciated that when the removably mounted portion of the heel structure has been subjected to considerable wear, 60 it may easily be removed and replaced by the wearer without the necessity of resorting to the services of a skilled artisan.

In the modified form of the invention illustrated in Figs. 6 to 9, inclusive, it will be appreciated 65 that substantially the same fundamental principles obtain. Fig. 6 illustrates a plan view of a modified form of removably mounted heel structure which is provided with an inwardly projecting flange 20 adapted to cooperate with the 70 undercut portion of the permanently mounted heel structure with which it is associated. Inferiorly this heel is provided with a downwardly extending dovetail recess 21 adapted to receive a complementary dovetail projection formed upon 75 the permanently mounted portion of the heel

member with which it is adapted to be associated. It will be appreciated that this form of the invention utilizes, as did the preferred form, not only the forces of tension but the forces of compression for securing the removably mounted heel 5 member in position.

Fig. 7 discloses a still further modified form of the invention, showing a removable heel element having an inwardly projecting flange 24 adapted to be received within the undercut recess 12 surrounding the permanently mounted heel structure 10 and having a substantially D-shaped island 25 in the center thereof, which island portion is undercut to cooperate with a similarly shaped undercut recess formed in the permanently mounted portion of the heel to which this member is attached.

In the modified form of the invention illustrated in Figure 8, a removable heel element 27 is shown, which has an inwardly projecting flange 20 28 adapted to seat in the undercut recess of the permanently mounted heel member with which it is associated and has a circular channel 29 cut therein, the walls of the channel being undercut or downwardly sloping to cooperate with a complementary circular projection formed on the permanently mounted heel member with which it is associated.

In the still further modified form of the invention illustrated in Fig. 9, a heel element 30 is 30 shown adapted for removable mounting upon a complementary permanently secured heel member; and it will be seen that this member is likewise provided with an inwardly projecting flange 31 similar to the flange 16 described above and 35 adapted to tensionally engage the undercut portion of the permanently mounted heel member with which it is associated. This heel member is provided with a longitudinally extending dovetail projection 32 and a transversely extending 40 dovetail projection 33 which are adapted to be seated in complementary dovetail recesses formed in the permanently mounted portion of the heel structure with which this removable element is 45 associated.

In the still further modified form of the invention illustrated in Figs. 10 and 11, a removably mounted heel construction is shown which utilizes substantially the principles taught in this application and provides an exterior appearance 50 substantially similar to that of a rubber heel which has been secured in the conventional manner.

In this form of the invention, it will be seen 55 that the construction shown provides a permanently secured heel member 35 formed of leather or similar material, which is provided with a D-shaped channel 36 therein of substantially dovetail shaped cross section. The removably mounted heel element 37 has an outer configuration 60 substantially identical in size and shape with that of the permanently mounted heel member 35, and is provided with an upwardly extending D-shaped ridge 38 of dovetail cross section adapted to seat 65 in the channel 36 and secure the heel in position thereon. It will be appreciated that this latter modification permits the use of a removable heel element of considerably simpler construction than the forms shown above.

In the form of the invention illustrated in Fig. 70 12, I have shown a removably mounted heel member 40 which is designed to cooperate with a permanently mounted heel member 41, and which utilizes a dovetail construction 42 to provide the 75 interfitting relation between the edge portions of

the member 40 and the heel portion 41 instead of the inwardly directed flange and undercut portion utilized in connection with the above embodiments of the invention. This construction has been found to be somewhat simpler than the above construction and provides a satisfactory gripping action. It will be appreciated that this form of the invention likewise includes an interfitting dovetail 43 between the removable and 5 permanently mounted portions of the heel section, in order that both the forces of tension and compression will be utilized for securing the parts in predetermined relative position.

The above embodiments of the invention are 10 merely illustrative of the generic inventive concept presented herein and defined in the subjoined claims. Many other and further modifications, falling within the scope of the claims, will be apparent to those skilled in the art.

15 20 I claim:

1. A shoe construction including, in combination, a relatively rigid heel member permanently secured to the shoe with which it is associated, said heel member having a channel of dovetail cross section formed in the bottom face thereof, said channel being of substantially uniform width and being substantially uniformly spaced from the marginal edge of the bottom face of said heel member, and a resilient heel member having a configuration substantially congruent to 25

said permanent heel member, said resilient heel member having an endless ridge of dovetail cross section in the upper surface thereof adapted to seat within the channel formed in said permanent heel member to retain said resilient heel member in position with respect thereto with the lateral edges of said permanent and resilient heel members lying flush with each other. 5

2. A shoe construction including, in combination, a permanently mounted relatively rigid heel member, said heel member having a generally D-shaped channel of dovetail cross section formed in the bottom face thereof, the outer edge of said channel being substantially uniformly spaced from the marginal edge of said heel member, 10 thereby forming an undercut projection of substantially D-shaped form in the central portion of the bottom face of said heel member, and a resilient heel member adapted for securement thereto, said resilient heel member having a substantially D-shaped ridge of dovetail cross section formed on the upper surface thereof adapted to seat within said channel, said resilient heel member having an exterior configuration substantially the same as said permanently mounted 15 heel member, whereby when secured in position, the adjacent lateral surfaces of said heel members will lie flush with each other. 20 25
